(57) CLAIM

The ornamental design for a cooking pot, as shown and described.

DESCRIPTION

FIG. 1 is an exploded top perspective view of a cooking pot according to the new design;

FIG. 2 is another exploded top perspective view of the cooking pot of FIG. 1;

FIG. 3 is a top perspective view of a cooking pot according to the new design;

FIG. 4 is another top perspective the cooking pot of FIG. 3;

FIG. 5 is a bottom perspective view of the cooking pot of FIG. 3;

FIG. 6 is another bottom perspective view of the cooking pot of FIG. 3;

FIG. 7 is a top view of the cooking pot of FIG. 3;

FIG. 8 is a bottom view of the cooking pot of FIG. 3;

FIG. 9 is a front side view of the cooking pot of FIG. 3;

FIG. 10 is a back side view of the cooking pot of FIG. 3;

FIG. 11 is a right side view of the cooking pot of FIG. 3;

FIG. 12 is a left side view of the cooking pot of FIG. 3; and,

FIG. 13 is an enlarged perspective view of detail 13 from FIG. 3.
